UNITED STATES PATENT OFFICE.

JOSEPH P. MANTON AND GEORGE H. REMINGTON, OF PROVIDENCE, R. I.

IMPROVEMENT IN POWER-CAPSTANS.

Specification forming part of Letters Patent No. 155,877, dated October 13, 1874; application filed September 5, 1874.

To all whom it may concern:

Be it known that we, JOSEPH P. MANTON and GEORGE H. REMINGTON, both of the city and county of Providence, State of Rhode Island, have invented a new and useful Improvement in Power-Capstans; and we do hereby declare that the following is a full, clear, and exact description thereof, which will enable others skilled in the art to make and use the same, reference being had to the accompanying drawings forming part of this specification, in which similar letters of reference indicate corresponding parts.

Figure I is an elevation of our improved capstan, partly in view and partly in section, showing the relative positions of the engines A A, the worm C, the worm-gear D, the driving-head E, and their relation to the vertical shaft G, as also the positions of the capstan-head X, the capstan-barrel Q, the wildcat R, and friction-brake N, with the central shaft G. Fig. II is a horizontal section, showing the power-gear I in section and the wildcat R partly in view. Fig. III shows the arrangement of the engines, with the worm C, worm-gear D, and the driving-head E, and their relation to the vertical shaft G.

Our invention consists in the direct application of engine-power to a capstan or windlass, in which a capstan-barrel, a wildcat, friction-brake, and compound gear are combined, so that by a simple manipulation the engine-power may be applied to either or both the barrel or wildcat; and, also, the compound gear may be readily applied to either, and so the power increased, while, by a simple manipulation, the whole may also be worked by hand with capstan-bars, in the usual manner, and both by hand or engine power, in either direction.

In the drawings, X is the capstan-head, furnished with socket-holes S, for the insertion of the capstan-bars. This capstan-head X is permanently keyed on the shaft G. Next to and below the capstan-head is the capstan-barrel Q, fitting the shaft G, but turning freely on the same. Below this is the wildcat R, which turns freely upon the sleeve Z, which encompasses the shaft G, and also turns freely on the same. Onto the upper end of the sleeve

Z a disk-plate, Y, is secured, having locking-sockets corresponding with a locking-socket in the capstan-barrel Q.

When, now, the key-block L' is placed into the locking-socket at the base of the barrel, so as to engage in one of the sockets of the disk-plate Y, the sleeve Z and the capstan-barrel are firmly secured one to the other, and revolve together, but freely, around the shaft G.

Cast onto the lower end of the sleeve Z, and forming part of the same, is a circular disk-plate, having a number of locking-sockets—some in the top part of the same, to receive the key-block M, and others in the periphery, to correspond with the locking-socket L.

When, now, the locking or key block M is inserted into the locking-socket in the base of the wildcat R, the key-block L' being still in place at the base of the barrel, it will be seen that, by means of the sleeve Z, the disk Y, and the key-blocks L' and M, the capstan-barrel Q, the wildcat R, and the sleeve Z are firmly secured together, but are still free to revolve on the shaft G, and not affected by the revolving of the capstan-head X, or the shaft, while both are under complete control of the friction-brake N, the brake-surface forming the lower rim of the wildcat, surrounded by the friction-strap N, which can be operated by either or both of the two eccentric levers O and hand-spikes P.

The toothed gear-wheel II is cast in one piece with the circular disk, containing locking-sockets corresponding with the locking-socket L, and is firmly keyed or secured to the shaft G, and revolves with the same.

If, now, the key-block is placed into the socket L, the wildcat R, the barrel Q, and capstan-head X are all firmly secured to the shaft G, and, when the capstan-head is turned by the capstan-bars in either direction, the whole will turn with the capstan-head. If, now, the key-block L' is removed, the barrel will be loose and turn freely, while the wildcat is still secured to the shaft G, and will only turn with the capstan-head X. If, however, instead of the key-block L' the key-block M is removed, the barrel Q will remain firmly attached to the shaft G and move with the same, while the wildcat R may freely revolve on the sleeve Z.

The base of the capstan consists of a circular plate, marked in the drawings O', which is firmly secured to the deck, and which forms the journal or bolster for the shaft G. This base-plate has a rim projecting above the deck, and in which a locking-socket is made at K. Resting on this base-plate and surrounding the shaft G, on which it turns freely, is the disk-plate W, carrying the intermediate pinions I, which are secured to said plate by studs, on which they turn, and gear into the toothed pinion H, and also into the toothed rim H'.

When, now, the key-block L is removed and placed in the locking-socket K, the disk-plate W is secured to the base-ring O', and cannot revolve around the shaft G or with the same. The toothed gear H, therefore, revolving with the shaft, turns the intermediate pinions I on their studs, and they, in turning, engaging into the toothed rim H', turn the same; and this, being cast in one piece with the sleeve Z, or firmly secured to the same, turns the capstan-barrel and wildcat, both together or either separate, as may be desired, with increased power at a slower speed than the capstan-head, and in the opposite direction.

All the above changes and operations are described as being done by hand-power, and the use of capstan-bars placed into the sockets S in the capstan-head X. The same changes and operations may also, and as efficiently and more promptly, be performed by the direct application of engine-power, which we will now further describe.

The central shaft G extends below the deck, and rests in the step V to this shaft, and below the deck is firmly keyed the driving-head E, in the periphery of which a number of key-sockets are cast, as is shown in Fig. III. Surrounding this driving-head, and turning freely on the shaft G, is the worm-gear D, having key-sockets corresponding with the key-sockets in the driving-head E.

When, now, the key-block F is placed as shown, so as to fit into both the sockets of the worm-wheel D and driving-head E, the capstan can be worked by the engines A A, the connecting-rods of which are secured to the cranks B B, and thus give rotary motion to the worm C, which engages into the worm-gear D, and so applies the power of the engines to the shaft G, and thus, at the will of the operator, is made, by a few and simple manipulations, to drive any part or all the parts of the capstan in either direction, and either by simple or multiplied power.

Having thus described the relations of the different parts of our improved power-capstan, we will now explain the manipulations required to perform all the different functions by engine-power, premising, first, that when the key-block F is in its place, our capstan is a direct-engine-driven capstan, and when the key-block F is removed it is a hand-power capstan, all the change required be-

ing the replacing or removing of the key-block F.

When a chain is to be hauled in by the capstan at full speed, the same is laid down on and around the wildcat, the barrel being required loose. Place the key-block K into the key-socket L, the key-block L' being removed; now start the engines, and the wildcat will haul the chain. A rope is now required to be hauled. Replace the key-block L', and the barrel and wildcat will move together, and both rope and chain are being hauled. If they are both required to be paid out, the friction-brake will perfectly control the operation. If, now, the power is to be increased, remove the key-block from L, and place the same in the socket at K, when the power will be increased and the speed diminished.

When the key-blocks M, K, and F are removed, and the key-blocks L and L' are in place, the capstan will be a simple hand-capstan, in which the capstan-head and barrel revolve in either direction at the same speed.

When, now, the key-block M is inserted, we have a hand-capstan and wildcat combined, the barrel, wildcat, and capstan-head revolving together.

If, now, the key L is removed and placed into the key-socket K, we have a hand-power capstan, the barrel and wildcat moving in the opposite direction of what the capstan-head is moving, and slower, but with increased power.

If, now, the key-block F is inserted, we have a direct-engine-driven capstan, in which all the above changes can be effected, and the capstan under all these various conditions driven by the engines A A.

All these numerous changes are effected by four simple key-blocks, at all times accessible, easily handled, not liable to get fast, or bend, or out of order.

The friction-brake is very powerful, as two eccentric-lever blocks, O O, are secured one on each end of the friction-strap, each operated by a hand-spike. The power may therefore be doubled, as both the levers may be manned; or, in the ordinary use, either one may be used separately.

Having thus described our invention, we claim as new, and desire to secure by Letters Patent as our invention—

1. The combination of the engines A A, worm C, and worm-gear D, with the driving-head E secured to the shaft G, and the worm-gear D by the key-block F, as and for the purpose set forth.

2. A capstan, consisting of a central shaft driven by engine-power, having a driving-gear and capstan-head secured to said shaft, and a capstan-barrel and wildcat revolving freely around said central shaft, when both together, or each separately, can be locked so as to revolve with the shaft, substantially as and for the purpose herein described.

3. In a power-capstan, the toothed rim H' and sleeve Z, made in one piece or secured together and to the disk-plate Y, and provided with locking-sockets by which the barrel and wildcat, either or both, may be locked to and turn with the sleeve Z and the driving-shaft, as and for the purpose set forth.

4. In combination with a capstan or wind-

lass, the friction-strap N, when both ends of the strap are connected to levers, so that either or both may be operated, as described.

JOSEPH P. MANTON.

GEORGE H. REMINGTON.
